UNITED STATES PATENT OFFICE.

GEORGE S. O'FLYN, OF NEW YORK, N. Y.

DESIGN FOR A GAME-BOARD.

SPECIFICATION forming part of Design No. 29,774, dated December 6, 1898.

Application filed November 3, 1898. Serial No. 695,401. Term of patent 3½ years.

To all whom it may concern:

Be it known that I, GEORGE S. O'FLYN, of the city of New York, (borough of Brooklyn,) in the county of Kings and State of New York, have invented and produced a new and original Design for a Game-Board, of which the following is a full, clear, and exact description.

Reference is to be had to the accompanying drawings, forming a part of this specification, in which similar characters of reference indicate corresponding parts in both the views.

Figure 1 is a plan view of the game-board, and Fig. 2 is a sectional side elevation of the same on the line 2 2 in Fig. 1.

The design in its entirety consists of an open box A, the bottom of which appears with square recesses B and fields C, irregularly arranged alongside some of the recesses B, with longitudinal and transverse intersecting

ridges D, separating the recesses from each other. The top faces of the ridges and fields are in the same horizontal plane, and the bottoms of some of the recesses are ornamented with the representation of a flag E and a flag-staff appearing rising out of the center of a circular white field F in a rectangular black background G.

The leading feature of the design consists of recesses and fields irregularly arranged relatively to each other and ridges separating the recesses from one another.

I claim—

The design for a game-board, as herein shown and described.

GEORGE S. O'FLYN.
